(57) **CLAIM**

I claim the ornamental design for a grate, as shown and described.

DESCRIPTION

FIG. 1 is an isometric view of the grate;

FIG. 2 is a front elevational view thereof;

FIG. 3 is a rear elevational view thereof, the opposite side
being symmetrical;

FIG. 4 is a first side elevational view thereof;

FIG. 5 is a second side elevational view thereof;

FIG. 6 is a bottom plan view thereof; and,

FIG. 7 is a top plan view thereof.
